US00D870906S

(12) **United States Design Patent** (10) **Patent No.:** **US D870,906 S**
Bruder (45) **Date of Patent:** **** Dec. 24, 2019**

(54) **THERAPEUTIC EYE MASK**

(71) Applicant: **BRUDER HEALTHCARE COMPANY, LLC**, Alpharetta, GA (US)

(72) Inventor: **Mark H. Bruder**, Alpharetta, GA (US)

(73) Assignee: **BRUDER HEALTHCARE COMPANY, LLC**, Alpharetta, GA (US)

(**) Term: **15 Years**

(21) Appl. No.: **29/677,244**

(22) Filed: **Jan. 18, 2019**

(57) **CLAIM**

The ornamental design for a therapeutic eye mask, substantially as shown and described.

DESCRIPTION

FIG. 1 is a perspective view of a therapeutic eye mask according to an example embodiment of the design, showing an example application and environment of use over the eye region of a person.

FIG. 2 is a perspective view of the therapeutic eye mask shown in FIG. 1.

FIG. 3 is a side view of the therapeutic eye mask shown in FIG. 1 (the opposite side views being mirror images of one another).

FIG. 4 is a front view of the therapeutic eye mask shown in FIG. 1.

FIG. 5 is a back view of the therapeutic eye mask shown in FIG. 1.

FIG. 6 is a top view of the therapeutic eye mask shown in FIG. 1; and,

FIG. 7 is a bottom view of the therapeutic eye mask shown in FIG. 1.

In the drawings, the broken lines depict environmental subject matter only and form no part of the claimed design.

1 Claim, 3 Drawing Sheets
